VOLTAGE REGULATING RELAY

Eric Douglas Tobias Norris and Norman Newton,
Hollinwood, England, assignors to Ferranti
Electric Inc., New York, N. Y.

Application February 4, 1938, Serial No. 188,308
In Great Britain February 12, 1937

1 Claim. (Cl. 172—239)

This invention relates to voltage regulating relays as used especially though not exclusively in transmission and distribution circuits, and also in individual load circuits for the control of variation of the voltage applied either to a succeeding portion of the circuit or to the load.

In certain cases it is desirable to maintain the voltage on the output side of the voltage regulator within specified limits under all load conditions in spite of voltage variations on the input side; in other cases it is desirable that the voltage regulator should not only correct for the supply voltage variations but it should also cause the output voltage to rise in a predetermined manner with increase of load. Various types of voltage regulators for the above purposes are known, e. g., induction regulators, on-load tap-changing boosters and moving coil regulators.

When the voltage correcting function is being performed, it is desirable that the operation should be carried out as quickly as possible, and a regulator which operates instantaneously would be ideal for the purpose.

Automatic operation is at the present time obtained according to one system by means of a voltage sensitive relay which controls a contactor and auxiliary relays, which in turn start a motor operating the voltage regulator. In another known system, the voltage regulator is controlled by means of a servo-motor operated by a balanced oil-pressure system. In neither system is very high speed operation attainable, so that the response to voltage fluctuations falls far short of the ideal.

It is the purpose of the present invention to provide means for greatly decreasing the time occupied in voltage regulating so as to approach more nearly to the ideal instantaneous control.

The invention may be applied to those types of voltage regulators in which a contact-making voltmeter is associated with operating mechanism, i. e., mechanism serving to effect a change in voltage on the output side of the voltage regulator. The invention is particularly suitable for use in conjunction with the moving coil regulator described in United States Patent No. 1,901,768, in which case the current to the motor driving the moving coil is directly controlled by the regulator. By suitable choice of gearing and of the power of the driving motor any desired high speed of operation may be obtained. It is possible, however, for the speed of operation to become so high that the operating mechanism corrects the voltage in a shorter time than that taken by the contact-making voltmeter to reset and

there is then a likelihood that the operating mechanism will over-run and change the output voltage beyond the desired limit before the contact-making voltmeter is able to reset and stop the motor. Under these conditions the contact-making voltmeter will then operate again but in the reverse direction; the cycle will thus be repeated and the regulator will hunt continually.

In practice, however, it is found that when means are adopted to reset the contact-making voltmeter quickly, the mechanical force exerted on the contact-making voltmeter armature by these means is liable to cause the contact-making voltmeter armature to over-run and make contact in the reverse direction. Hence it is desirable to associate means with the contact-making voltmeter either for preventing or for rendering innocuous such an over-run of the contact-making voltmeter.

The object of the present invention is to provide an automatic voltage regulator with means for either preventing the contact-making voltmeter from over-running when resetting or for rendering innocuous the effect of such over-run.

The present invention in brief consists in an automatic voltage regulator for adjusting voltage to a desired value, comprising current operated mechanism having a pair of coils for actuating voltage adjusting means, a reversible motor, operative mechanical connections between said motor and said mechanism, a source of electrical energy for said motor, electrical connections between said source and said motor comprising only one energising circuit, an electromagnetic contact-making voltmeter capable of resetting at a speed which is sufficiently high for it to be liable to overrun in consequence of the mechanical force exerted thereon during the resetting for controlling said energising circuit for the actuation of said motor in a direction governed by the required change of voltage and contact-making voltmeter-overrun effect-prevention means comprising a first and second contactor in series with said coils respectively.

Referring to the accompanying diagrammatic drawings—

Figure 1 illustrates one convenient arrangement embodying the present invention in one form.

Figure 2 illustrates a modified detail of Figure 1.

Figure 3 illustrates a modified form of device for preventing over-run and/or for quick resetting.

Figure 4 illustrates a form of device for render-

ing innocuous over-run of the contact-making voltmeter of Figure 1.

The invention will now be described as applied in one form by way of example to a voltage regulator embodying an astatic contact-making voltmeter, comprising an enclosed type mercury switch *a* embodying a centre connection joined to terminal *b* and two side contacts *c*, *d*. The switch is carried on a bell-crank lever *e* pivoted at *f* and actuated by the pull on the plunger *g* by an electromagnet coil *o*. The electromagnet is of known form such that the pull on the plunger by the electromagnet is substantially independent of the displacement of the plunger throughout its working range. A reversible electric-induction motor *h* embodies two windings *i* and *j* so arranged in conjunction with a condenser *2* that when one is energised the motor turns in one direction and effects movement of a short-circuited coil in a voltage adjusting device *30* for voltage regulation.

When the other winding is energised the motor reverses and moves the short-circuited coil in the opposite direction.

Two additional coils *k*, *m* are provided, the former coil being in series with switch contact *c*, coil *i* and a terminal *n*, and the latter coil being in series with the contact *d*, coil *j* and the terminal *n*. The coils *k*, *m* are disposed in juxtaposition to the operating coil *o* on the relay electromagnet, the direction of the windings of the coils *k*, *m* and currents through them being such that when those relay contacts which are adapted to lower the output voltage, viz., contacts *d*, *p* are closed, the coil *m* decreases the pull on the plunger *g* whereas when the relay contacts *c*, *p* are closed, the coil *k* increases the pull on the plunger *g*.

Conveniently the windings *k*, *m* are arranged in practice to encircle the winding *o* of the relay.

An arm *q* is attached rigidly to the lever *e* and at a short distance from the lower end of the arm is a catch plate *r* having two notches *s*, *t* separated by a short tongue *u*. An armature *v* pivoted at *w* carries the catch plate, which armature co-operates with an auxiliary electromagnet *x* having a winding which is connected in parallel with the coil *j* of the motor *h*.

The terminals *n*, *b* are connected to an A. C. current source.

In operation, when the line voltage decreases, the magnetic force on the relay plunger *g* is reduced, causing the plunger to fall. This closes the switch contacts *c*, *p* which by energising the motor coil *i* starts the motor *h* in such a direction as to raise the output voltage. When the contacts *c*, *p* close, however, a current passes through the additional coil *k* in such a direction as to augment the pull of the operating coil *o* on the plunger; this increase in the pull may be arranged to have any desired value. The relay is thus caused to reset in a time which is made slightly shorter than that required for the correction of the voltage to the normal value. The over-run of the motor *h* after opening of the contacts *c*, *p* will, however, due to the high speed of operation, accomplish the remainder of the voltage correction, or at least will bring the output voltage within a range equal to the sensitivity of the relay.

The additional coils *k*, *m* being connected in series with the switch contacts, only operate when the motor *h* is excited. As soon, therefore, as the relay has reset sufficiently to open the motor circuit, the additional coil which has been in operation is no longer energised, the resetting

force disappears, and the relay is ready to operate again under its normal condition.

When the relay is in the neutral position shown in Figure 1, the catch plate *r* rests on a support *y* clear of the relay arm *q* and therefore it has no effect upon the operation of the relay. As soon as the relay has operated to cause bridging of the contacts *p*, *d*, thus starting the motor, the auxiliary electromagnet *x* becomes energised and consequently raises the armature *v* together with the catch plate *r*. The subsequently operative resetting force on the relay causes the switch *a* to move towards the neutral position, but in doing so the relay arm engages the notch *s* in the catch plate *r* and the switch is prevented from running past the neutral position by the engagement of the relay arm *q* with the tongue *u* of the catch plate. The armature and catch plate are associated with a damping device *z* in order that they may be retained in the raised position for a short interval of time after the switch has moved approximately into the neutral position. When the auxiliary electromagnet *x* releases the armature *v* and catch plate *r*, the relay is ready for further operation, the commencement of which is unaffected by the presence of the auxiliary electromagnet *x* and its co-operating parts.

When the relay operates to bridge contacts *c*, *p*, the electromagnet *x* is again energised since it is in parallel with the winding *i* by way of a condenser *2*. The action is similar during resetting of the relay to that described above, the arm *q* now, however, entering the notch *t*.

On account of the condenser *2* the electromagnet *x* is energised when either the contacts *c* and *p* or *d* and *p* are closed but the direction of rotation of the rotor of the motor *h* depends upon whether one or other of these pairs of contacts are closed.

In a modified arrangement of Figure 1, the winding of the electromagnet *x* is connected in series with the two actuating coils *i*, *j* of the motor *h* as shown in Figure 2, the operation being similar to that already described.

In an alternative arrangement illustrated in Figure 3 for preventing the relay from over-running the neutral position when resetting, a tongue *9* of magnetic material is attached rigidly to the bell-crank lever *e* of the relay mechanism. An auxiliary electromagnet *10* is disposed with one of its pole-pieces on one side of the tongue and its other pole-piece on the other side of the tongue. The axial disposition of the parts is such that when the relay is in the neutral position the tongue lies between the poles of the auxiliary electromagnet and when the relay operates, the tongue moves from between the poles. The winding of the electromagnet *10* is connected in parallel with an actuating coil of the motor *h*.

It will be seen therefore that the electromagnet *10* is normally unenergised so that operation of the relay from the neutral position is unaffected. When one set of contacts of the relay has closed, however, the auxiliary electromagnet *10* is energised and by its attractive force on the tongue of magnetic material, prevents the relay from over-running the neutral position.

The winding of the electromagnet *10* of Figure 3 may if desired be connected in series with actuating coils of the motor.

The tongue *9* of Figure 3 may be of sufficient width to enable the auxiliary electromagnet *10* to provide the resetting force for the relay by exerting a pull on the tongue when the relay

movement is in either of its contact making positions.

- In a further modification illustrated in Figure 4, the relay is restored rapidly to its neutral position, and no attempt is made to prevent overrunning of the neutral position, but a device is incorporated to prevent hunting due to the overrun. In this embodiment two contactors are used, the winding 16 of the first contactor being connected in series with the winding *i* of the motor which latter winding causes rotation to occur in the "raise" direction, while the winding 17 of the second contactor is connected in series with the winding *j* of the motor which latter winding causes rotation to occur in the "lower" direction. A switch 18 operated by the first contactor is connected in series with the contacts *c*, *p* of the relay switch mechanism and with winding 17, and a switch 19 operated by the second contactor is connected in series with the contacts *p*, *d* of the relay switch mechanism and with winding 16. A time lag device (not shown) is fitted to each contactor to delay the resetting of the contactors.
- When the relay operates for example in the "raise" direction, by bridging contacts *c*, *p* the contactor winding 17 is energised, thus opening the switch 19 and it is thus impossible for the motor to be energised in the "lower" direction even though the relay over-runs the neutral position sufficiently to close the "lower" contacts *p*, *d* when resetting. Although the contactors operate extremely quickly when energised, there

is a delay in resetting after the de-energisation of the contactors due to the time lag devices. The time lag on the contactors is such that the relay switch mechanism *e* is allowed to return to the neutral position before the contactor that has been opened resets. 5

Although a number of arrangements have been described herein, it will be evident that many other arrangements are possible without exceeding the scope of the invention. 10

We claim as our invention:

An automatic voltage regulator for adjusting voltage to a desired value, comprising current operated mechanism having a pair of coils for actuating voltage adjusting means, a reversible 15 motor, operative mechanical connections between said motor and said mechanism, a source of electrical energy for said motor, electrical connections between said source and said motor comprising only one energising circuit, an electromagnetic contact-making voltmeter capable of resetting at a speed which is sufficiently high for it to be liable to overrun in consequence of the mechanical force exerted thereon during the resetting for controlling said energising circuit 20 for the actuation of said motor in a direction governed by the required change of voltage and contact-making voltmeter-overrun effect - prevention means comprising a first and second contactor in series with said coils respectively. 25 30
